RAZOR STROP

Albert F. Staples, Bridgewater, Mass.

Application July 13, 1936, Serial No. 90,354

5 Claims. (Cl. 51—200)

This invention relates to hand razor strops and more especially to such razor strops suitable for use in sharpening safety razor blades.

Generally speaking the invention relates to that type of razor strop which is supported upon the hand of a user in a position wherein the razor blade may be brought into the most advantageous engagement with the strop by a turning of the hand to meet the usual to and fro movement. The principal object of the invention is to provide a hand razor strop which is firmly supported in a fixed position but may be yieldingly supported so that in all the changing relative positions of the strop and razor during the stropping operation the strop will consistently present to the blade stroke the same progressively depressed surface as is presented by a wall supported strop.

To the accomplishment of this object and such others as may hereinafter appear, as will readily be understood by those skilled in the art, the invention comprises the features and combinations of parts hereinafter described and then particularly pointed out in the appended claims.

The nature and scope of the invention will best be understood from a description of the preferred embodiment thereof illustrated in the accompanying drawing, in which:

Figure 1 is a perspective view, on a reduced scale, showing the improved razor strop supported in operative position on the slightly bent hand of a user;

Fig. 2 is a plan view, partly broken away, of one end of the improved razor strop;

Fig. 3 is an elevational view of the end of the razor strop as shown in Fig. 2;

Fig. 4 is a view of the under side of the strop at the opposite end thereof from that shown in Fig. 2; and

Fig. 5 is a sectional view at the line 5—5 of Fig. 4.

In the preferred embodiment of the invention 10 indicates, in general, the improved razor strop which, in this instance, includes a stropping strip 11 of leather or other suitable material, the length thereof being somewhat less than the distance from the finger tip 12 to the wrist 13. Thus the palm is slightly cupped when the strop is mounted on the hand, the strip 11 being free of the palm and fingers. In order that the strop may be controlled to move as a unit with changing positions of the hand, one end of the strip 11 is attached to the finger tip 12 and its other end is attached to the wrist or base of the hand 13.

For this purpose a piece of flexible material 14, 55 which may be soft leather, is applied to the under

face 15 of the strip 11 at its outer end 16 preferably by stitching around its outer end as at 17, 18 and 19 forming a socket. The socket piece 14 is wider than the strip 11 and considerably wider at its inner edge 20 which is left unstitched so that a finger pocket 21 is formed on the back of the strip at its outer end 16, the mouth of the pocket facing inward. A wrist strap 23 is secured to the inner end 22 of the strip 11 by having one end 24 thereof stitched or otherwise secured across it. The free portion 25 of the wrist strap thus extends laterally from the strip 11 and is of such a length as to encircle the wrist 13. A plurality of spaced openings 26 are formed in the strap any one of which may be engaged with a lacing hook 27, set in its secured end 24. It will be understood that the openings 26 provide for the adjustment of the strap for encircling wrists of varying sizes.

In use one of the fingers, preferably the middle finger, is inserted in the pocket 21 and the strip 11 forming the strop body is laid across the palm of the hand which is cupped to bring the end 22 of the strip into position at the wrist where it is secured by the strap 23. The hand strop will be made in sizes so that a strop length may be chosen that will be suitable for the length of the hand of any user. In any event the position of the stropping strip on the hand should be such as to cause it to bridge across between the finger tip and wrist thus holding it away from the palm of the hand when the hand is opened and the strop is tautened. In this position the strop will yield as a razor blade is brought into stropping contact therewith, thus preserving the advantages of a wall strop. If the strip 11 is made so long that when secured at the wrist it lies against the palm and fingers an uneven surface is presented to the razor blade which is detrimental to sharpening its edge.

Due to the fact that both ends of the strip 11 are secured in a manner to hold the strop taut over the cupped palm of one hand, the user is free to flex that wrist during the blade stropping operation thereby to turn that hand and the attached strop as a unit and present the strop at the precise angle for the most effective sharpening sweep of the blade held in the other hand. Thus the hand strop of this invention may be manipulated for presentation to the razor blade in the same efficient manner as when using a wall strop.

When the stropping strip 11 is relatively thin and quite flexible the insertion of the finger into the pocket 21 will cause its end to bend around

the finger and flex out of its flat condition. In order to prevent such bending and to provide a flat stropping surface clear to the outer end of the strop so as to permit stropping contact by the blade edge from end to end as the latter is passed over the strop, a piece of relatively stiff sheet material 28 such as thin fibre board is applied to the under face of the strip 11 beneath the pocket forming member 14. Obviously the stiffening member 28 need not be wider than the strip 11 or longer than the finger pocket and may conveniently be attached to the strip 11 by the same stitching that is used in attaching the flexible piece 14. In any event the stiffening member 28 lying between the strip 11 and the finger inserted in the pocket 21 will preserve flatness at the outer end of the strip thereby insuring a uniform engagement by the edge of the blade throughout its travel back and forth.

20 The nature and scope of the invention having been indicated, and its preferred embodiment, operation and use having been specifically described, what is claimed as new, is:—

25 1. A razor strop adapted to be secured to the human hand, comprising a strip of stropping material having a surface adapted to be presented for substantially its entire area for stropping purposes, a piece of flexible material secured at a plurality of its edges to the edges of the sides 30 and one end of said strip opposite the stropping surface, the securement at the sides being for substantially the entire length of the piece, said piece being wider than said strip whereby the same is bulged with respect to said strip to form 35 a flexible pocket adapted to receive a finger of the user's hand and conform to the shape thereof to hold the adjacent end of said stropping strip to the hand.

40 2. A razor strop adapted to be secured to the human hand, comprising a strip of stropping material having a surface adapted to be presented for substantially its entire area for stropping purposes, a piece of non-metallic flexible material secured at a plurality of its edges to the edges 45 of the sides and one end of said strip opposite

the stropping surface, said piece being wider than said strip whereby the same is bulged with respect to said strip to form a flexible pocket adapted to receive a finger of the user's hand and conform to the shape thereof to hold the adjacent end of said stropping strip to the hand, and a piece of relatively stiff material inserted between said strip and piece adapted to substantially hold said strip against deformation at said end of the strip. 10

3. A razor strop to be supported over the palm of the hand comprising a strip of stropping leather having a finger receiving pocket on its rear face at its outer end and a wrist strap at its inner end, one side of said finger pocket being formed 15 by said outer end of the stropping strip and its other side being formed by a piece of flexible sheet material of such length as to enclose the end of a finger, said sheet material being slightly wider than the stropping strip and lying against 20 the rear face of the stropping strip at said outer end and marginally secured thereto except across its wider inner transverse edge thereby causing said inner edge to bulge and to present an open pocket mouth facing the inner end of the stropping strip. 25

4. A razor strop according to claim 3 having a piece of relatively stiff sheet material within the pocket for reinforcing the outer end of the stropping strip inserted between the stropping strip 30 and said piece of sheet material and preventing it from curving about a finger inserted in said pocket.

5. A razor strop adapted to be secured to the hand and wrist, comprising a stropping strip, a 35 piece of flexible sheet material overspreading and secured against the outer end of said strip on the side disposed adjacent the hand and forming therewith a pocket having an open inner end and a closed outer end for receiving the end of 40 one of the fingers thereby disposing said strip lengthwise of the hand, and means at the inner end of said strip for securing said end to the wrist.
